Calvin Brown
ATTORNEY.

UNITED STATES PATENT OFFICE

WILLIAM A. RICE, OF LOS ANGELES, CALIFORNIA

EXTRACTOR

Application filed June 22, 1929. Serial No. 372,979.

This invention relates to devices for the extraction of various articles from the surface of an object such as, for instance, the extraction of weeds and vegetable growth such as beets and the like, and in such a manner as to obviate the necessity of the operator stooping in the performance of the extracting operation.

An object of the invention is the provision of a device of the character stated which will, in the case of extraction of weeds, not sever the weed but completely remove the weed from the ground.

Another object is the provision of an extracting device which is so arranged and constructed as to provide for a gradually increasing lifting effect upon the object to be removed.

Another object is the provision of an extracting device which when engaging work will gradually increase its extracting effort on said work, and finally lift the work from an object.

Another object is the provision of an extracting device which is simple of construction, durable, efficient in operation, easy to handle, and generally superior in use and serviceability.

With the above and other objects in view, the invention consists in the novel and useful provision, formation, construction, association, and relative arrangement of parts, members and features, all as shown in a certain embodiment in the accompanying drawings, described generally, and more particularly pointed out in the claims.

In the drawings:

Figure 1 is a perspective view of my improved extractor shown engaging a weed,

Figure 2 is a front elevation of the extractor and showing the fork member,

Figure 3 is a side elevation of the extractor, and

Figure 4 is an elevation of a spring member used in practicing the invention.

Referring to the drawings, the improved extractor includes a base member *a*, a fork *b*, means *c* normally tending to separate the base and fork, and means *d* constituting a handle secured to the base *a*.

The handle is conventional in form and is adapted to be socketed in a member *1* secured to the base *a*. The base *a* constitutes an elongated strip having a curved object engaging foot *2*. The said base is provided with a pair of spaced, outstanding knuckles *3* and *4*, between which is pinned the fork *b*. This fork includes an elongated body or shank portion *5* and a pair of spread or fork ends *6*. The fork portion curves relative to the shank, as best shown in Figure 3. However, I use the term "fork" in its broadest sense, as including the shank as well as the end *6*. The curve of the foot *2* is toward the fork or, in other words, in front of the base. The means *c* constitutes a spring of the character shown in the figures, although any spring or other medium adapted to normally cause separation between the base and the fork would be equally satisfactory. In the present instance, the spring includes a wire member having spaced ends *7* and *8* which are attached to the base by being passed through openings in the base or in some manner fastened to the base and said wire member coiled at *9* and *10* and provided with an intermediate U-shaped part *11*. This U-shaped part bears against the back of the fork and is in slidable relation thereto. I may provide the back of the base with an outstanding ledge *12* and may likewise provide an outstanding ledge *13* for the fork.

The operation, uses and advantages of the invention are as follows:

The fork is inserted at the base of the weed or whatever object is to be extracted, as shown in Figure 1 at 14. If the ground is hard, the insertion of the fork may be difficult. To this end, pressure may be brought to bear upon the ledge *13* through the medium of the foot of the operator. However, assuming that the fork is engaging the weed as shown, the handle is then moved in the direction of the arrow 15 in Figure 1 and the curved foot of the base will gradually slide upon the surface of the ground, as shown at 16, and compress the spring *c*. It is evident that the foot will act as a fulcrum and as the handle is pushed down, the spring compression becomes increasingly great. This causes an ever increasing extracting force upon the roots of 100

the weed due to the gradual compression of the spring until such time as the roots give way and the spring by suddenly expanding will throw the fork upwardly and likewise throw the weed out from the ground. The principle of gradual compression of the spring to provide an increasing extracting force is thought to be novel. Furthermore, as before stated, all operations may be maintained while the operator is in an erect position.

It is obvious that various changes and modifications and variations may be made in practicing the invention in departure from the particular showing of the drawings without departing from the true spirit thereof.

I claim:

1. In an extractor, a support having a curved foot at one end and a socket at the opposite end, a handle for said socket, a fork swingingly carried by the support, resilient means between said support and fork whereby when the fork engages an object and the handle is moved, the curved foot acts as a fulcrum to cause the resilient means to be placed in compression.
2. In an extractor, a support formed with a curved foot, a handle for said support, a fork swingingly carried by the support, resilient means between said support and fork whereby when the fork engages an object and the handle is moved, the curved foot acts as a fulcrum to cause the resilient means to be placed in compression.
3. In an extractor, a support formed with a curved foot, a handle for the support, a fork hinged to said support, the lengthwise dimension of said fork being greater than the lengthwise dimension of the support, resilient means between the said support and fork whereby when the fork engages an object and the handle is moved, the curved foot acts as a fulcrum to place the resilient means in compression.
45. In testimony whereof, I have signed my name to this specification at Los Angeles, California, this 31st day of May, 1929.

WILLIAM A. RICE.
